US00D789206S

(12) **United States Design Patent** (10) **Patent No.:** **US D789,206 S**
Chen (45) **Date of Patent:** **** Jun. 13, 2017**

(54) **BOTTLE**

(71) Applicant: **Fang-Pin Chen**, Chia Yi Hsien (TW)
(72) Inventor: **Fang-Pin Chen**, Chia Yi Hsien (TW)
(**) Term: **14 Years**
(21) Appl. No.: **29/512,572**

(22) Filed: **Dec. 19, 2014**

(51) LOC (10) Cl. **09-01**

(52) U.S. Cl. **D9/542**
USPC ....

(58) **Field of Classification Search**

USPC .... D9/435, 436, 440, 445, 447, 449, 450, D9/453, 452, 442, 500-505, 520-522, D9/529, 571, 550, 556, 546, 562-572, D9/512, 530, 532-543, 548, 516, 574, D9/575, 526, 558-561, 565-567, 569, D9/519, 726-729, 740, 746, 764, 738, D9/752, 759, 767, 772-783, 904; D3/202, 203.1-203.4, 203.7; D28/82, D28/4-8; D19/66, 115-179; D7/396.2, D7/509-511, 523, 590; D6/515, 542; D14/114, 485; D24/119, 197; D34/1, 2 CPC B65D 88/54; B65D 83/00; B65D 83/04; B65D 11/04; B65D 11/00; B65D 90/02; B65D 90/12; B65D 23/102; B65D 21/024; B65D 1/42; B65D 1/46; B65D 1/02; B65D 1/0207; B65D 1/023; B65D 1/04; B65D 1/10; B65D 1/12; B65D 1/14; B65D 1/16; B65D 1/165; B65D 1/18; B65D 1/0246; B65D 1/0238; B65D 1/0223; B65D 1/0215; B65D 13/02; B65D 23/00; B65D 35/00; B65D 35/02; B65D 35/04; B65D 35/56; B65D 35/08; B65D 39/00; B65D 39/0005; B65D 39/0029; B65D 41/0428; B65D 41/04; B65D 41/0435; B65D 41/0442; B65B 7/28; A61J 9/00; A45F 5/00; B29C 33/005
